STAIR STRUCTURE

Filed Sept. 12, 1925

FIG. 1.

FIG. 2.

FIG. 3.

FIG. 4.

FIG. 5.

INVENTOR.
Braziel R. Burnham,
BY
Frank A. Carter,
ATTORNEY.

UNITED STATES PATENT OFFICE.

BRANCIL R. BURNHAM, OF WHITNEY, SOUTH CAROLINA.

STAIR STRUCTURE.

Application filed September 12, 1925. Serial No. 56,023.

My invention relates to improvements in stair structures, and more particularly in the stringers thereof, and consists essentially of a sheet-metal strip cut and bent to form a 5 stringer provided with supporting and attaching parts at the ends, and with tread supports extending inwardly from the front-edge portion, and also with riser supports if desired, all of peculiar construction, and as hereinafter more fully described.

The primary object of my invention is to provide a simple and inexpensive stringer for stairs or steps, which stringer is adapted 15 to be readily fastened in place, and to have treads, and risers when desired, readily fastened thereto, it being understood that two stringers are used in the construction of each flight of steps or stairs. The stair 20 structure produced with the aid of these stringers is very rigid and durable, and serves every purpose of a stair structure of the old type.

The stringers are punched out of and 25 formed from sheet-metal, hence are comparatively light in weight.

Other objects and advantages will appear in the course of the following description.

I attain the objects and secure the advantages of my invention by the means illustrated in the accompanying drawings, in which—

Figure 1 is a plan of a strip or blank which has been punched from a piece of sheet-metal and cut or slit and perforated in readiness to be formed into a stringer embodying a practical form of my invention; Fig. 2, a front elevation of a stair structure in which are incorporated two 35 of the stringers formed from blanks such as that shown in the preceding view; Fig. 3, a top plan of one of said stringers; Fig. 4, a vertical section through a stair structure showing a slightly modified form of stringer; and, Fig. 5, a front end elevation 40 of the left-hand stringer which belongs in the structure illustrated in Fig. 4.

Similar reference characters designate similar parts throughout the several views.

Although I have illustrated in the drawings a flight of steps having only three treads, and in the modified form three risers in addition, it is to be understood, of course, that there may be any reasonable number 55 of treads and risers provided the stringers be made to accommodate the same.

In the first view is shown a strip or blank 1 of sheet-metal, provided at the upper end with a projection 2 and at the lower end with a projection 3, and having cut inwardly from one longitudinal edge thereof slits 4—4. The longitudinal edges of the strip 1 are parallel with each other. The bottom edge of the strip 1, at the right of the lug 3, would if continued be parallel 60 with the slits 4, and such edge portion and said slits are at the proper angle to form the riser portions of the complete stringer, which latter is indicated by the numeral 5 in Figs. 2 and 3.

The projection 2 is bent inwardly on the dot-and-dash line 6, which line is a continuation of the upper edge of the blank 1, to form a vertical supporting and securing lug or flange 7 at the upper end 75 of the stringer 5. The lower, left-hand corner portion of the blank 1, together with the projection 3, is bent inwardly on the dot-and-dash line 8 to form a bottom support 9 for the stringer 5, and said projection 80 is bent upwardly on the dot-and-dash line 11 to form a horizontal riser flange or lug 10.

Three triangular portions of the blank 1 are bent inwardly along three dot-and-dash 85 lines 12 to form a corresponding number of horizontal tread supports 13. The intermediate line 12 extends between the inner end of the upper slit 4 and the outer end 90 of the lower slit 4, the upper line 12 extends from the outer end of said upper slit to the angle formed by the projection 2 with the upper end of the blank 1, the short upper end of said projection being a continuation of said line, and the lower line 95 12 extends from the inner end of the lower slit 4 to the angle formed between the bottom and right-hand edges of said blank. The lines 8 and 12, if extended, would all be parallel with each other.

There are, in the present example, two openings 14 in each of the projections 2 and 3, and the same number of similar openings in each of the triangular portions of the blank 1 which produce the tread supports 12, and there are also two similar openings in the portion of said strip which is set off by the dot-and-dash lines 8 and 11.

In Fig. 2 three treads 15 are shown mounted on the tread supports 13 of the 110 two stringers 5 therein appearing, and said treads are secured to said supports by means

of screws 16 and nuts 17, there being a pair of such screws and a pair of such nuts adjacent to each end of each tread to secure the same to the support below, and the screws passing through the openings 14 in such support. The riser portions of the stringers 5 below the bottoms of the treads 15 are indicated by the numeral 18.

The support 9 at the bottom of each stringer 5 rests on the floor or other part of the building structure, and is secured thereto by screws, bolts, or other suitable means, to accommodate which the openings 14 are provided in the part of the blank 1 that forms said support, such floor or part and fastening means not being shown. The lug 7 at the upper terminal of each stringer 5 rests against a timber or other support of the building structure (not shown), and is secured thereto by means similar to those employed in securing each of the supports 9 in place. The openings 14 in the projection 2 of the blank 1 are for the accommodation of the aforesaid securing means.

If desired, a riser (not shown) may be bolted to the lugs 10 through the openings 14 therein.

If it be desired to provide the stair structure with risers, as 19 in Fig. 4, a lip or flange 20 is turned inwardly from the vertical riser portion of each stringer 5 beneath each tread support 13 with which such stringer is provided, except at the bottom where either the lug 10 may be utilized, or in place thereof a lug 21 which will presently be described, and said risers are secured to said flanges and lug by means of screws and nuts similar to those employed to secure the treads 15 to their supports. There are two openings 14 in each of the flanges 20 and in either the lug 10 or the lug 21 for two of the screws 16. The screws 16 for the risers 19 pass through the latter adjacent to the ends of the same.

In the construction of the stringer illustrated in Figs. 4 and 5, which stringer is designated by the numeral 5^a, a narrow horizontal flange 22 is formed on the bottom of said stringer, in place of the larger flange or support 9, and the riser lug 21 is bent inwardly from the forward end of said stringer, instead of being bent upwardly from the forward end of said larger flange or support. The narrow flange 22 is designed to be bolted or otherwise secured, like the support 9, to the floor or other part of the building structure. This base construction of the stringer 5^a might be substituted for the base construction of the stringer 5, and vice versa.

Except in the particulars hereinbefore pointed out, the two stair structures illustrated in connection herewith are generally similar to each other.

Obviously some other means besides the

screws 16 and nuts 17 may be employed for securing the treads and risers to the stringers.

More or less change in the shape, size, construction, and arrangement of some or all of the parts of this stair structure, in addition to those hereinbefore specifically pointed out, may be made without departing from the spirit of my invention or exceeding the scope of what is claimed.

What I claim as my invention, and desire to secure by Letters Patent, is—

1. In a stair structure, a sheet-metal stringer cut and bent inwardly at one longitudinal edge to form horizontal triangular tread supports, with the base of each of these triangular supports at one end and the apex at the other end, and bent at the lower terminal to form a horizontal base support, said stringer being flat throughout except at said longitudinal edge and the ends.

2. In a stair structure, a sheet-metal stringer cut and bent inwardly at one longitudinal edge to form horizontal triangular tread supports, with the base of each of these triangular supports at one end and the apex at the other end, and bent at the lower terminal to form a horizontal base support which is bent upwardly at the front edge to provide a vertical riser-supporting lug, said stringer being flat throughout except at said longitudinal edge and the ends.

3. In a stair structure, a sheet-metal stringer cut and bent inwardly at one longitudinal edge to form horizontal triangular tread supports, with the base of each of these triangular supports at one end and the apex at the other end, bent at the lower terminal to form a horizontal base support which is bent upwardly at the front edge to provide a vertical riser-supporting lug, and bent inwardly at the upper terminal to provide an attaching lug, said stringer being flat throughout except at its longitudinal edge and the ends.

4. In stair structure, a sheet metal stringer strip having both longitudinal edges free and originally parallel with each other, and adapted to be slit inwardly from one of said edges, the slits being equidistant apart, to have triangular portions of said strip, each defined by one of said slits, an imaginary line between the inner and outer ends of two adjacent slits, and the intervening part of the longitudinal edge of the strip from which the slits extend inwardly, bent at right-angles to the main portion of the strip, to form tread supports, each triangular portion being bent on the aforesaid imaginary line.

5. In stair construction, a sheet-metal stringer having both longitudinal edges free and originally parallel with each other and provided with projections at the ends, said strip being adapted to be slit inwardly

from one of said edges, the slits being equidistant apart, to have triangular portions of said strip, each defined by one of said slits, an imaginary line between the inner and outer ends of two adjacent slits, and the intervening part of the longitudinal edge of the strip from which the slits extend inwardly, bent at right-angles to the main portion of the strip, to form tread supports;

each triangular portion being bent on the aforesaid imaginary line, and to be bent at the lower terminal to form a horizontal base support, and to have said upper projection bent inwardly to form an attaching lug and said bottom projection bent upwardly to form a lug for the attachment thereto of a riser.

BRANCIL R. BURNHAM.
